UNITED STATES PATENT OFFICE

OTTO W. GREENE, OF ELYRIA, OHIO, ASSIGNEE TO INDUSTRIAL RESEARCH CORPORATION, OF TOLEDO, OHIO, A CORPORATION OF DELAWARE

CHARGE-FORMING DEVICE

Application filed January 31, 1921, Serial No. 441,184. Renewed October 8, 1928.

This invention relates to devices for causing an intimate mixture of a gas and a liquid, especially those devices which are used to form a combustible charge from air and liquid fuel to be used in an internal combustion engine.

The general object of my invention is the provision of means for thoroughly breaking up and vaporizing a liquid by means of an air current. Another object is to produce this breaking up, or atomization, in two stages, one atomization occurring without the venturi and the second occurring as the preliminary mixture enters the venturi.

Another object is to lead the air for the preliminary atomization from an unrestricted portion of the venturi, so that there is a difference of pressure to cause the flow of air for said preliminary atomization.

Another object is to provide an annular chamber about the venturi in which the preliminary mixture of air and liquid takes place, and which delivers said preliminary mixture to a restricted portion of the venturi evenly all around said portion.

Another object is the provision of means to by-pass a portion of the air which enters the Venturi tube so that said by-passed air will serve to form a preliminary mixture of air and liquid and then to admit this mixture into said Venturi tube.

Other objects and those relating to simplicity of structure and economies of manufacture will appear herein as I proceed with a detailed description of that particular embodiment of my invention which for the purposes of illustration I have shown in the accompanying drawings, in which

Figure I is a longitudinal section through the mixing valve and showing its connections to the engine and the fuel and air pipes.

Figure II is an end elevation on an enlarged scale of the removable Venturi member, and

Figure III is a side elevation of the same with a part in section.

Similar reference characters refer to similar parts throughout the several views.

1 represents the valve body of the air and fuel mixing valve which supplies an explosive

mixture to the internal combustion engine 2. 3 is the air intake pipe which may be secured to the valve body by a flange, as shown, or by any suitable means. 4 is the liquid fuel supply pipe leading from the fuel tank, not shown. 5 is an air choke valve for cutting off the air supply to the mixing valve by the operation of the handle 6. Any form of choke valve may be used, but I prefer to use a rotary valve, as shown, having a curved end surface 7 whereby the cross section of the air passage may be accurately adjusted and indicated by the position of the handle 6. 8 is a removable Venturi member which together with the passage 9 in the valve body forms the complete Venturi tube. The member 8 abuts a shoulder on the valve body 1 and is provided all around its end with a number of small radial grooves 10. The member 8 is also chamfered at its end as shown at 11 (Figure III) which thus provides an annular space 12 between member 8 and the valve body 1. The liquid fuel enters this annular space 12 from the fuel supply pipe 4, preferably first passing through a strainer 13 and a replaceable nozzle 14. During normal running of the engine a small amount of air also enters this annular space 12 by way of two drilled holes 15 in the flare of the member 8, thence through the annular space 16 formed between the valve body 1 and the member 8, and thence through a number of peripheral grooves 17 leading into the annular space 12, as shown. The suction of the engine acting at the throat of the venturi where the suction is greatest, brings liquid fuel from pipe 4 up into the annular space 12. This same suction draws a small amount of air through the holes 15 and thence through the grooves 17 into the space 12 which mixes with the liquid fuel and breaks it up into atomized particles in space 12. These atomized particles then pass evenly all around through the radial grooves 10 at a very high velocity into the air stream at the point of maximum speed of air and are therefore further broken up and vaporized. If the air choke valve 5 is turned to reduce the amount of air admitted through pipe 3 it will increase the suction acting upon the liquid fuel and thus cause a

richer mixture to be supplied to the engine. Thus it is seen that both the quantity and quality of the mixture is controlled by the valve 5. When valve 5 is adjusted to increase the amount of charge the mixture is made leaner and vice versa. The mixing valve as shown acts to maintain the same proportionate mixture when applied to engine use, through large engine speed variation. Where the load governs the speed, an increase in revolutions makes the suction pressure at the Venturi throat greater tending to draw its proportionate increase in amount of fuel and air. The greater air speed also causes a corresponding increase in the suction pressure at the flare of the venturi, and as a result the first stage of atomizing remains unchanged except that the increased suction draws more fuel through the line, which is necessary to maintain the mixture. With a fixed nozzle in the fuel line the valve 5 becomes only a regulator of the mixture, either too rich or lean with no chance to throttle the motor except at the expense of fuel economy. The lever is made convenient to operate in order that when starting a much enriched mixture can be used by moving the lever over to close the valve.

For starting purposes a priming cup 20 is provided on the top of the valve body 1. The cup 20 is preferably formed integrally with the valve body, but if desired it may be formed separately and be attached thereto. When starting the engine priming fluid is inserted in the cup 20, the air choke valve 5 is almost closed, and the engine is turned over. The priming fuel passes down through the pin hole passage 21 into the space 16, thence through the peripheral grooves 17 to the annular space 12 and thence through the grooves 10 to the engine. Sufficient air to make a very rich mixture for starting passes by the choke valve 5 and mixes with the priming fuel at the throat of the venturi.

The pin hole 21 is so small compared to the two holes 15 that during normal running the air admitted through hole 21 can have no very appreciable effect. The slight amount of air which is admitted therethrough mixes in space 16 with the air passing through holes 15 and thereafter acts as if it all passed through the holes 15.

While I have described in more or less detail a certain embodiment of my invention I do not wish to be limited thereto, as it is obvious to those skilled in the art that other embodiments and modifications may be made without departing from the scope of my invention, as defined in the appended claims.

60 What I claim is:

1. In a mixing device, a Venturi tube, a chamber in close proximity to a restricted portion of said venturi, means for supplying a liquid to said chamber, means for supplying air to said chamber evenly all around said

chamber for mixing with the liquid therein, and means for admitting the air and liquid from said chamber into said venturi, said last mentioned means including a plurality of channels spaced about said tube and in connection with the chamber. 70

2. In a mixing device, a Venturi tube, a chamber in close proximity to a restricted portion of said venturi, means for supplying a liquid to said chamber, means including channels formed in the wall of the Venturi tube for supplying air to said chamber for mixing with the liquid therein, and means for admitting the air and liquid from said chamber into said venturi. 75

3. In a mixing device, a Venturi tube, a chamber in close proximity to a restricted portion of said venturi, means for supplying a liquid to said chamber, means including channels formed in the wall of the Venturi tube for supplying air to said chamber for atomizing the liquid therein, and means for admitting the air and liquid from said chamber into said venturi. 80

4. In a mixing device including a mixing chamber, a Venturi tube, an annular chamber around said Venturi tube, means for supplying a liquid to said annular chamber, means for leading air from a less restricted portion of said venturi into said annular chamber for mixing with the liquid therein, including a plurality of closely adjacent axially extending channels positioned about the tube, whereby a uniform air distribution to the mixing chamber is accomplished and means for admitting the air and liquid from said annular chamber into said Venturi tube at a restricted portion thereof. 95

5. In a mixing device, a Venturi tube, a mixing chamber in proximity to said Venturi tube, means for supplying liquid to said chamber, a by-pass for leading air from a less restricted portion of said Venturi tube into said chamber for mixing with the liquid therein, including a plurality of closely adjacent axially extending channels positioned about the tube, whereby a uniform air distribution to the mixing chamber is accomplished and means for admitting the air and liquid from said chamber into said Venturi tube at a restricted portion thereof. 105

6. In a mixing device, a tube having a restricted portion; an annular chamber surrounding said tube in close proximity to the restricted portion of said tube; means for supplying a liquid to said chamber; a second chamber surrounding said tube at a less restricted portion thereof; means for admitting air to said second chamber; means including a plurality of passageways connecting said chambers; and means for admitting the resulting mixture of fuel and air into said tube. 110

7. In a mixing device, a Venturi tube; an annular chamber surrounding said tube in 115

close proximity to the restricted portion thereof; means for supplying a liquid to said chamber; a second chamber surrounding said Venturi tube at a less restricted portion thereof; means for admitting air into said second chamber; communicating passageways between said chambers; means for admitting the resulting mixture of fuel and air into said Venturi tube through openings located at the most restricted portion of the tube.

8. In a mixing device, a Venturi tube; a chamber surrounding said tube in close proximity to the restricted portion thereof; means for supplying a liquid to said chamber; a second chamber surrounding said tube; means for admitting air from said Venturi tube to said second chamber; means including a plurality of passageways connecting said chambers; and means for admitting the resulting mixture of liquid and air into said Venturi tube at the most restricted portion thereof.

9. In a mixing device, a tube having a restricted portion; a chamber surrounding said tube in close proximity to the restricted portion thereof; means for supplying liquid to said chamber; a second chamber surrounding said tube; means for admitting air to said second chamber through openings in the walls of said venturi at a less restricted portion thereof; means for connecting said chambers including a plurality of passageways; and means for admitting the resulting mixture of liquid and air into said venturi through circumferentially spaced openings arranged in the wall of said venturi at the most restricted portion thereof.

In testimony whereof, I affix my signature.
OTTO W. GREENE.
